US0D1015290S

(12) **United States Design Patent** (10) Patent No.: **US D1,015,290 S**
(45) Date of Patent: ** Feb. 20, 2024

(54) **ELECTRONIC DEVICE**

(71) Applicant: **Samsung Electronics Co., Ltd.**, Suwon-si (KR)
(72) Inventors: **Seung-Ho Jang**, Suwon-si (KR); **Da-Wi Lee**, Suwon-si (KR); **Jong-Bo Jung**, Suwon-si (KR); **Mi-Ri Lee**, Suwon-si (KR)
(73) Assignee: **Samsung Electronics Co., Ltd.**, Suwon-si (KR)
(**) Term: **15 Years**

(21) Appl. No.: **29/844,814**(22) Filed: **Jul. 1, 2022****Related U.S. Application Data**

(62) Division of application No. 29/770,218, filed on Feb. 10, 2021, now Pat. No. Des. 966,249.

Primary Examiner — Bridget L Eland*(74) Attorney, Agent, or Firm* — NSIP Law**CLAIM**

We claim the ornamental design for an electronic device, as shown and described.

DESCRIPTION

FIG. 1 is a rear perspective view of an electronic device showing our new design;

FIG. 2 is a rear view thereof;

FIG. 3 is a front view thereof;

FIG. 4 is a left-side view thereof;

FIG. 5 is a right-side view thereof;

FIG. 6 is a top view thereof;

FIG. 7 is a bottom view thereof; and,

FIG. 8 is a front perspective view thereof.

The broken lines in the figures depict portions of the electronic device which form no part of the claimed design.
